R. HUFF.
DOOR HANGER.
APPLICATION FILED MAY 28, 1913.

1,109,229.

Patented Sept. 1, 1914.

THE MORRIS PETERS CO., PHOTO LITHO., WASHINGTON, D. C.

UNITED STATES PATENT OFFICE.

ROBERT HUFF, OF PASSAIC, NEW JERSEY, ASSIGNOR TO THE "BOX CAR FLUSH DOOR COMPANY" INCORPORATED, A CORPORATION OF NEW YORK.

DOOR-HANGER.

1,109,229.

Specification of Letters Patent. Patented Sept. 1, 1914.

Application filed May 28, 1913. Serial No. 770,327.

To all whom it may concern:

Be it known that I, ROBERT HUFF, a citizen of the United States, residing at Passaic, in the county of Passaic and State of New Jersey, have invented a new and useful Door-Hanger; and I do hereby declare the following to be a full, clear, and exact description of the invention, such as will enable others skilled in the art to which it appertains to make and use the same.

This invention relates to an improved door hanger, adapted for either the upper or lower portion of the door.

In practical fields the details of construction may necessitate alterations falling within the scope of what is claimed.

The invention comprises further features and combination of parts, as hereinafter set forth, shown in the drawings and claimed.

20 In the drawings:—Figure 1 is a perspective view of a fragmentary part of a freight car, showing the door thereof equipped with the improved hanger construction. Fig. 2 is a sectional view on line 4—4 of Fig. 1. Fig. 3 is a sectional view on line 5—5 of Fig. 2. Fig. 4 is a sectional view on line 6—6 of Fig. 1.

Referring more especially to the drawings, 1 designates a car, which may be constructed in any suitable manner having a door opening 2. The door opening 2 and the vertical longitudinal edges of the door may be correspondingly so constructed, so as to permit the door to easily enter the door opening to assume a tight berth.

The upper track rail 5 comprises an elongated flat bar, which is secured to the upper portion of the car by means of bolts 6, which are passed through the sleeves or thimbles 7 and through the side of the car as shown at 8 and provided with nuts 9. Other means than the bolts may be used for securing the track rail 5 in position. Secured to the lower portion of the side of the car is a series of angular bracket castings 10, by means of bolts or other devices 11. Each bracket casting is constructed with an angular seat 12. The vertical flange 13 which forms a part of the angular seat 12 is reinforced relative to the body or horizontal portion 14 of the bracket casting, by means of a web 15. Secured to the vertical flanges 13 of the bracket castings by any suitable means, such as bolts 16 and in the seats of

55 said bracket castings is the lower track rail

17, which likewise consists of an elongated flat bar.

Secured to the outer face of the door by means of bolts 18 are plates 19 having laterally extending ears or lugs 20 which are pivoted at 21 between the ears or lugs 22, which form integral parts of the sleeves 23. These sleeves 23 are riveted or otherwise secured at 24 to the rocking rods 25 and 26. The lower ends of the rods 25 and 26 have thrust bearings in the lower hangers 27, which are bifurcated as shown at 28, to receive the lower guide rail 17. The hangers 27 are provided with additional bifurcations 29 extending at right angles to the bifurcations 28, and in the crotches of the bifurcations 29 roller bearings 30 are arranged. These roller bearings are provided with flanges 31 assisting in holding the rollers in place, which rollers engage the track rail 17, while their upper circumferences contact with the curved portions of the crotches of the bifurcations 29, as indicated at 32, thereby permitting the rollers to easily rotate, as the door is moved horizontally and in close proximity to the car.

The upper hangers 33 are provided with elongated portions 34 having grooves 35 to receive the upper track rail 5. The upper ends of the rods 25 and 26 have thrust bearings in the plates or members 36, which plates or members 36 and the upper ends of the rods 25 and 26 are arranged in the bores 37 of the barrels 38 of the upper hangers 33, there being coil springs 39 interposed between the plates 36, and the closed ends 40 of said bores. The springs 39 act to hold the hangers 33 in engagement with the upper track rail 5.

From the foregoing it will be noted that there has been devised a simple and efficient door hanger construction, particularly adapted for holding and supporting the car door to its berth in the door opening, so as to remain flush with the outer face of the side of the car body, and which will prevent the door to move horizontally and in close parallel proximity to the side of the car, and one which has been found desirable and practical.

The invention having been set forth, what is claimed as new and useful is:—

1. In improvements in door hanger construction, upper and lower rails, hangers thereon having grooves to receive said rails

and to be engaged thereby, one of said hangers having a transverse groove extending in a plane transversely of one of said rails, a spool roller bearing engaging between the 5 transverse groove and one of said rails having flanges engaging the inner and outer faces of said hanger to hold the spool roller bearing in place, rods having bearing connections with said hangers, and connections 10 between the rods and the door.

2. In improvements in door hanger construction, a pair of supporting rails, pairs of hangers on said rails, each hanger of one pair having a groove arranged in a plane 15 parallel with its supporting rail and engaging therewith, and provided with a second groove extending at right angles to the first groove, said second groove being deeper

than the first groove, a spool roller bearing comprising a cylinder of less radii than 20 the radii of the crotch of the second groove and engaging the same, the cylinder being substantially corresponding in length with the crotch of the second groove, said roller bearing having flanges to engage the inner 25 and outer faces of said hanger to prevent displacement of the roller bearing, and means of connection between said hangers and the door.

In testimony whereof I have signed my 30 name to this specification in the presence of two subscribing witnesses.

ROBERT HUFF.
